ELECTRIC TABLE LAMP

Douglas F. Illian, Evanston, Ill.

Application April 7, 1939, Serial No. 266,550

3 Claims. (Cl. 240—81)

The present invention relates to electrically lighted lamps in general and particularly to an electric table lamp. More specifically the invention comprises an electric lamp provided with a multiplicity of light-radiating surfaces at a distance from the main source of light and including light-conducting elements which function as the supporting legs of the lamp.

It is an object of the invention to provide a new and novel electrically lighted lamp. Another object of the invention is to provide a lamp in which a principal light source provides light rays which are conducted internally of the lamp structure to be emitted at spaced points. Still another object of the invention is to provide a lamp in which light rays are emitted from spaced surfaces around the base of the lamp. A still further object of the invention is to provide a table lamp in which an electric light forms the main light source and in which light rays from said electric light are conducted thru light-conducting supporting legs to be discharged at an angle to their original directions. These and other more specific objects will be apparent from reading the following specification and claims and upon considering in connection therewith the attached drawing to which they relate.

Referring to the drawing in which a preferred embodiment of the invention is illustrated, and in which the same reference character refers to the same part of the various views:

Figure 1 is a side elevation of the lamp constructed in accordance with the present invention; and

Figure 2 is a vertical section upon the line 2—2 of Figure 1; and

Figure 3 is a transverse horizontal section upon the line 3—3 of Figure 1.

In the lamp constructed in accordance with the present invention an electric light bulb 1 is removably secured in a well known manner in its socket 2 embodying current-controlling means the manually depressible operating pins of which are evident at 3. Socket 2 is carried by a base comprising a plurality of supporting legs 5, each having an out-turned lower extremity and a major portion extended vertically thru openings 6 in upper and lower plates 7 and 8, respectively, of the base. The legs are suitably secured to the plates as by pins, nails or screws 9, or reliance may be placed entirely upon friction or the presence of glue, etc., the exact retaining means not being of the essence of the invention. It is important, however, that the upper ends of the legs 5 be exposed to light rays, either direct or re-

flected and preferably both, from the light bulb 1.

It is upon the upper plate 7, which like the lower plate 8 is preferably made of a material adapted to take a fine finish such as wood, or a resin, that the socket 2 in fact seats directly. 5 A pipe 11 connects fixedly to the bottom of the socket and extends downwardly thru plates 7 and 8 to have its lower screw-threaded extremity secured, by a nut 12, on the underside of plate 8. The openings 13 in the plates 7 and 8 thru which the conduit 11 extend are counterbored at their adjacent ends and a rigid appearance conduit 14 which encloses the pipe 11 seats therein. The effect of tightening the nut 12 is obviously to draw the socket 2 against the upper plate 7 and the plates 7 and 8 against the ends of the rigid conduit 14 to provide a rigid structure.

The pipe 11 provides a suitable channel for the current-conductor 15 which passes upwardly 20 therethru from the underside of plate 8 to be connected to the electrical connections provided internally of the socket 2 which may be of any well-known type.

A lamp shade 17 is mounted in the usual relationship to the bulb 1 by a divided supporting standard 18 which is clamped between the socket 2 and the plate 7 at its lower end and which seats the shade directly above the light bulb, the usual decorative clamping nut 19 being used as 30 manually operable retaining means.

As in the common lamp the electric bulb is supported at a height above the supporting surface and within a suitable shade having greater or lesser transparency. In the lamp constructed 35 in accordance with the present invention, however, the supporting elements or legs 5 are characterized by their light-conducting qualities and are so arranged that they face the light bulb 1 at one of their ends in each instance, so as to receive light from the source, and at their opposite ends are directed as to emit light rays at an angle to their direction at entrance. As the legs are curved and rounded at their lower extremities to provide suitable rests necessarily the entrained 40 light must travel the curves. In the normal light-conducting medium light rays travel in straight lines but the rays must be bent as described in the instant invention. This result is 45 best accomplished by making the legs solid and of methyl-methacrylate.

The material of the legs 5 may be tinted to various colors as to give off light of any desired shade at the leg extremities. While most of the 55

light which is given off at the outer extremities of the legs 5 will have come directly to the legs from the light bulb 1 a part thereof at least will be light reflected by the bulb-enclosing shade 17.

5 Instead of tinting the legs 5 of the lamp to various colors in order to give off light of a desired shade at their lower ends the legs themselves may be uncolored and there may be provided a colored disc or filter at the end of the 10 leg adjacent the light source. In Figure 2 a disc or filter 21 is illustrated at the upper end of one of the legs 5. If desired such filters can be provided on all the legs in the same color, in different colors, or may be omitted entirely.

15 I claim:

1. In an electric lamp comprising an electric light source and a base supporting said source, said base including a plurality of supporting elements each having an end exposed to said source and having the characteristic of transmitting and bending light without emitting same between its ends, the ends of said elements spaced from said source facing outwardly to emit light received from said source, spaced horizontal elements spacing said supporting elements, a conductor conduit extended between said horizontal elements, a connection at the upper end of said conduit to seat removably said light source, a current conductor extended upwardly thru said

conduit to said connection, and a shade enclosing said light source.

2. In an electric lamp comprising an electric light source and a base supporting said source, said base including a plurality of colored supporting elements each having an end exposed to said source and having the characteristic of transmitting and bending light without radiating same between its ends, said supporting elements being curved intermediate their ends to form 10 surface-contacting feet, the lower ends of said elements being spaced from said light source to emit colored light.

3. An electric lamp comprising an electric light radiating source and a base supporting said 15 source above a supporting surface, said base including a plurality of supporting legs arranged in a circle and exposed at their upper ends to light rays from said source, said legs being formed of a material having the characteristic 20 of transmitting light from one of its ends to the other without emitting light between said ends, the lower portions of said legs being turned outwardly and upwardly to form surface-contacting feet, and the lower ends of said legs being 25 directed outwardly to provide a plurality of spaced secondary sources of light at the base of said lamp.

DOUGLAS F. ILLIAN.
